UNITED STATES PATENT OFFICE.

JOSEPH RODERICK AND GENEVIEVE GRACE RODERICK, OF NEW YORK, N. Y.

BURGLAR-ALARM.

No. 813,917.

Specification of Letters Patent.

Patented Feb. 27, 1906.

Application filed April 10, 1905. Serial No. 254,850.

To all whom it may concern:

Be it known that we, JOSEPH RODERICK and GENEVIEVE GRACE RODERICK, citizens of the United States, residing at New York, in the county of New York and State of New York, have invented a new and useful Improvement in Burglar-Alarms, of which the following is a specification.

This invention relates to an improvement in alarm devices, and has special reference to burglar-alarms of a portable nature capable of and especially adapted for connection to door-knobs for sounding an alarm to warn the occupants of the dwelling or room of the attempted entrance of an intruder.

The object of the invention is to provide a cheap, simple, and neat device that is exceedingly sensitive and positive in its operation, one that may be readily attached to a door-knob, one that may be readily adjusted to an inoperative position to permit the occupants of the dwelling or room opening the door without sounding the alarm and without the necessity of removing the device from the door-knob, and also one in which a portion of the device which carries the alarm and mechanism for operating the same may be easily disconnected from the part attached to the door and the necessity of entirely removing the whole device thereby avoided.

A further object is to provide a device of a compact nature which permits of its being carried in one's grip or pocket, thus rendering it especially adapted for the use of travellers, and still a further object is to provide a construction in which but few parts are employed and the liability of the device as a whole getting out of order thus decreased.

With these briefly-stated objects in view the invention comprises certain details of construction and peculiar and novel arrangement of parts, as will be fully set forth in the following specification and pointed out in the claims, reference being had to the drawings, in which—

Figure 1 represents a portion of a door having our invention connected to the knob-shank and showing the device set. Fig. 2 is a similar view showing the alarm-carrying frame removed and illustrating the hanger to which the frame is connected arranged in position upon the knob-shank. Fig. 3 is a detail perspective view of the alarm-carrying frame of our invention. Fig. 4 and Fig. 5 are

detail views of the hanger which is connected to the knob-shank. Fig. 6 is a detail view of the releasing-bar. Fig. 7 is a detail view of the escapement, illustrating the arm carried thereby which is engaged by the releasing-bar. Fig. 8 is a sectional elevation of the device complete. Fig. 9 is a sectional elevation drawn on about the line 9 9 of Fig. 8. Fig. 10 is a horizontal sectional elevation drawn on about the line 10 10 of Fig. 8. Fig. 11 is a detail section drawn on the line 11 11 of Fig. 8; and Fig. 12 is a detail view showing the releasing-bar locked, in which position the escapement is locked against the escapement-wheel and the alarm-sounding mechanism locked against movement.

In carrying out our invention we employ a hanger A, having a hook portion A' at its upper end which engages the shank of the door-knob A² and is securely locked against movement upon the shank by a set-screw A³. The lower end of the hanger is provided with a shoulder A⁴, to which is pendulously hung the alarm-carrying frame B. A flange A⁵ is arranged at the outer end of the shoulder A⁴, as shown most clearly in Figs. 5 and 9 of the drawings, which prevents the frame B being accidentally disengaged from the hanger.

The alarm-carrying frame B comprises a circular lower portion B', from which extend two vertical arms B², which are connected at their upper ends, as at B³, to provide a suitable portion by which the frame is suspended from the hanger. A cross-bar B⁴ connects the arms about midway their length, the purpose of which will be explained hereinafter. A plate C is connected to the lower portion of the frame and carries an alarm D, the alarm-sounding mechanism E, including an escapement-wheel F, and an escapement anchor or pallet G, all of these last-mentioned parts being of substantially the same construction as now commonly employed. The escapement-anchor G is provided with the usual clapper-rod and clapper G', and to the latter is connected an arm H, which extends rearwardly through an opening C' in the plate C and thence upwardly and terminates in a flattened contacting end H', adapted to be engaged by the lower end of the spring-actuating releasing-bar I, which is supported in the frame B and which passes through an aperture in the cross-bar B⁴ and also through an aperture in the lower portion of the frame

down into a recess B^3 , provided in the lower circular portion of the frame in which also operates the arm H . A pin I' projects from the releasing-bar I , and surrounding the latter and between the pin I' and the lower apertured portion of the frame is a spring J , whose tendency is to normally elevate the pin and hold it from engagement with the contacting surface of the arm H .

5 When the releasing-bar I is pressed downwardly, its lower end will contact or engage the end of the arm H and press it downwardly, which through the medium of the clapper-rod G' will throw one end of the escapement-anchor G into engagement with the escapement-wheel F and lock the latter against movement, and in order to hold the parts in the position just described we provide the bar B^4 with a central recess, which

10 provides the shoulders B^6 upon either side of the same, and by turning the bar so that the pin will rest under either shoulder the releasing-bar will be held and locked in its lowermost position.

15 The operation of our invention is as follows: The hanger is first securely attached to the knob-shank, so that its lower portion will hang vertically, after which the frame is pendulously hung upon the shoulder of the hanger and the pin I' of the releasing-bar is then turned so that it is disengaged from the shoulder B^6 , when the spring will force the bar upwardly until its upper end engages the lower portion of the hanger. Now should a

20 person turn the door-knob, the hanger will be turned, but the frame will remain in a vertical position, and as the knob continues to turn the lower portion of the hanger will be moved from out of engagement with the releasing-

25 bar, when the spring will immediately force the bar to its extreme uppermost position and its lower end from engagement with the arm H , carried by the clapper-arm, and thus permitting the operation of the alarm-sounding mechanism, and consequently the alarm is sounded and a warning given to the occupants of the dwelling or room.

From the foregoing it will be seen that we provide an exceedingly cheap, simple, and efficient device for the purposes stated, and it will be particularly noted that by providing the escapement-anchor with an arm which is designed to be engaged by the releasing-bar our device may be readily locked against operation, so that the door may be opened without the alarm being sounded. It will also be noted that we provide a very simple and convenient attachment between the hangers and the frame which permits the latter being removed without the necessity of entirely disconnecting the alarm from the knob-shank.

The idea of providing a detachable connection between the hanger and the alarm-carrying frame and also a releasing-bar capable

of adjustment so that the alarm will not be sounded when the door is opened is of the greatest advantage and importance, as it is often desired to open the door after the device is adjusted thereto, which often happens, especially where children are playing about the household.

We do not claim, broadly, the idea of a hanger supporting an alarm-carrying frame, nor do we claim the alarm-sounding mechanism, as we are aware that similar devices have been patented; but our invention possesses certain improvements over the devices now upon the market, and

What we do claim, and desire to secure by Letters Patent, is—

1. A device of the kind described, comprising a hanger having a shoulder portion, a frame pendulously suspended upon the shoulder, an alarm mechanism carried by the frame and comprising an escapement-wheel and an escapement-anchor, the latter having a rod and bell-clapper connected thereto, an arm extending from the said rod, a spring-actuated rod, carried by the frame, a pin connected to the last-mentioned rod, shoulder portions arranged upon the frame and adapted for engagement by the pin, all substantially as and for the purpose specified.

2. A device of the kind described, comprising a hanger having a shoulder portion, the outer end of which is flanged, a frame pendulously suspended from the shoulder, said frame comprising a lower circular portion having arms extending therefrom and by which the frame is supported upon the hanger, a cross-bar connecting the arms, said cross-bar having an aperture vertically arranged therein and also having a recess upon its lower side by which shoulders are provided upon the bar, a rod operating through the aperture and also through an aperture in the lower portion of the frame, a pin carried by the rod, a spring surrounding the rod and engaging a pin and the lower apertured portion of the frame, an alarm mechanism carried by the frame and comprising an escapement-wheel and an escapement-anchor for engagement with the wheel, a rod having a bell-hammer connected to the escapement-anchor, an arm connected to the rod, said arm having its free end arranged in position to be engaged by the bar carried by the frame all substantially as and for the purpose set forth.

3. A burglar-alarm comprising a hanger and frame, an alarm mechanism carried by the frame, a spring-actuated rod slidably and revolvably journaled in the frame, and engaging the hanger and escapement of the alarm mechanism, and means carried by the rod for engagement with the frame by which the mechanism may be locked against operation irrespective of the movement of the frame or hanger.

4. A burglar-alarm consisting of a hanger and a frame pendulously supported from the hanger, an alarm mechanism carried by the frame, a rod slidably and revolvably held in the frame and engaging the hanger and escapement of the alarm mechanism when the alarm is set, a pin connected to the rod, a spring surrounding the rod and engaging the frame and pin, said spring being adapted to operate the rod to release the escapement when the hanger is disengaged from the rod, and a shoulder formed upon the frame for engagement by the pin whereby the rod may be locked against movement irrespective of the movement of the hanger or frame.
5. A burglar - alarm comprising a hanger and frame, an alarm mechanism carried by the frame, a spring-actuated rod revolvably and slidably mounted in the frame, and adapted for locking the alarm - sounding mechanism, a pin carried by the rod, a shoulder formed upon the frame for engagement by the pin whereby the said rod may be held into engagement with the alarm - sounding mechanism irrespective of the movement of the frame or hanger.
6. A burglar - alarm comprising a hanger and frame, said hanger having a shoulder

upon which the frame is held, the said frame comprising a lower circular recessed portion and vertical - extending arms connected at their upper ends, a cross-bar connecting the arms intermediate their ends, an alarm-sounding mechanism connected to the circular portion of the frame, an arm projecting from the escapement of the alarm mechanism and extending into the said recess, a rod slidably and revolvably held in the said cross-bar and lower portion of the frame, said rod engaging the hanger at one end and the arm of the escapement at its opposite end, a pin carried by the rod, a spring surrounding the rod and interposed between the base of the frame and pin, shoulders formed upon the cross-bar connecting the arms of the frame and adapted for engagement by the pin of the rod whereby the said rod may be held into engagement with the said arm of the escapement irrespective of the movement of the hanger or frame.
